(57) CLAIM

The ornamental design for a pistol case, as shown and described.

DESCRIPTION

FIG. 1 is a perspective view of a military style case, showing our new design;

FIG. 2 is a top view thereof;

FIG. 3 is a front view thereof;

FIG. 4 is a back view thereof;

FIG. 5 is a left side view thereof; and,

FIG. 6 is a right side view thereof.

A bottom view is not shown as it form no part of my design. Those portions of the figures shown in dotted lines form no part of my invention, but are included to show the context and environment of the invention.
